UNITED STATES PATENT OFFICE

FRANK H. BANNER, OF ROCHESTER, NEW YORK, ASSIGNOR TO GENERAL RAILWAY SIGNAL COMPANY, OF ROCHESTER, NEW YORK

GROUND-ROD CONNECTION

Application filed October 30, 1926 Serial No. 145,289.

This invention relates in general to a wire connection and a method of effecting the same, and has more particular reference to a means and method for connecting electric wires to ground rods.

In connecting a wire to a ground rod for effectually grounding the wire, it is important that a good electric contact, and a strong mechanical connection, be made between the wire and the ground rod.

In one usual form of connection, the wire is wound around one end of a smooth rod, as closely as the resiliency of the wire permits, and is then soldered to the rod surface by hand, while held in as close contact as possible with the rod. The soldering operation is not only a slow one, and hence relatively expensive, but it has been found in practice that upon driving the rod into the ground, the coils of wire often become loosened on the rod, and at times are jarred entirely free from their solder connection. Thus, both the mechanical and electrical connections are liable to easily become defective or entirely broken.

With the above and other considerations in mind, it is proposed, according to this invention, to provide a method and means for making a connection between a ground rod and a ground wire, which will satisfactorily overcome the above set forth defects.

Among the objects of the invention, are, to increase the efficiency, decrease the cost of production, and lengthen the useful life, of devices of the character in question.

Further objects, purposes, and characteristic features of the invention will appear as the description progresses, reference being had to the accompanying drawing, showing, solely by way of example, and in a wholly diagrammatic manner, one embodiment of the invention. In the drawing:—

Fig. 1 is an elevation of a device embodying the invention;

Fig. 2 is an elevation, at right angles to Fig. 1, with parts shown in section; and

Fig. 3 is a plan view diagrammatically illustrating one step in the process of making the connection.

Fig. 4 is a plan view of a detail.

Referring to the drawing, at 1 is shown a ground rod having an end 2 for being driven into the ground, and an end 3 for connection to a ground wire 4. Any suitable anchoring means can be used in connection with the rod, for holding it in place in the ground, without changing this invention.

The end 3 of the rod is cross drilled as at 5, and a helical groove or screw thread 6 is formed in its surface, running from the hole 5 outwardly toward the end of the rod, the thread being cut to a depth of approximately one half the diameter of the wire 4, to give the screw thus formed a diameter d (Fig. 65 2) at the root of the thread.

The wire 4, before being placed on the rod, is wound tightly around a mandrel 7, or is otherwise manipulated, to form a portion of the wire into a helical coil, having 70 a diameter d^1 (Fig. 3) which is substantially less than the diameter d . This coil of wire is then sprung slightly out against its natural resiliency, to then be passed over the smooth end 3 of the rod 1, and screwed into 75 the screw thread 6, the inner end of the wire being passed through hole 5 and securely held therein by means of a channel pin 8 (shown in detail in Fig. 4) which is driven into the hole as shown in the drawings to 80 somewhat flatten and deform the wire 4 and wedge it in place. The end 3 of the rod is then dipped into molten solder up to a point beyond the pin 8, whereby to securely solder the wire 4 to the rod 1 throughout the entire 85 length of its contact therewith.

By the above described method of fastening the wire to the rod, the natural resiliency of the wire operates to contract the coils of wire closely against the rod, whereas, 90 in the former method of initially winding the wire around the rod, this resiliency of the wire causes the same to spring away from the rod surface, and made soldering difficult and uncertain. That is, by the 95 present method, the springiness of the wire, which was heretofore disadvantageous, is now distinctly advantageous.

A further distinct advantage of the new method and product, resides in the time and 100

expense saved in the soldering operation, the dipping as described, being much quicker than when it was necessary to hold the wire coils against the rod and run solder along the wire turns by hand.

5 By this invention the desired end has been attained of quickly and cheaply fastening a wire to a rod, with a strong mechanical, and a good electrical, connection between the two members.

10 The above rather detailed description of one embodiment of this invention is given solely by way of illustration, and is not intended, in any manner whatsoever, in a limiting sense. Obviously the invention can assume many physical forms and is susceptible of numerous modifications, and all such forms and modifications are intended to be embraced by the invention, as come within 15 the scope of the appended claims.

20 Having described my invention, I now claim:

1. In combination, a ground rod, a hole in the rod, a wire pinned in the hole, a helical groove in the rod, the wire being wound around the rod to lie in the said groove.

2. In combination, a ground rod, a hole in the rod, a wire pinned in the hole, a helical groove in the rod, the wire being wound around the rod to lie in the said groove, and solder connecting the rod and wire.

3. In combination, a ground rod having a cross drilled hole therein, a helical groove in the rod terminating at one end adjacent the hole, a wire having one end held in the hole by a channel pin and an outwardly sprung helical coil portion received in the groove to resiliently embrace the rod, and a layer of solder covering the wire coil and adjacent portion of the rod and connecting the wire to the rod.

4. A method for making a ground rod connection, comprising, forming a helix in a wire, forming a screw thread on a portion of a ground rod with the diameter of the root of the thread greater than the inner diameter of the helix, threading the wire helix onto said screw thread by springing the helix open sufficiently to receive the rod, cross drilling the rod at one end of the thread, and fastening one end of the wire in the hole by means of a channel pin.

5. A method for making a ground rod connection, comprising, forming a helix in a wire, forming a screw thread on a portion of a ground rod with the diameter of the root of the thread greater than the inner diameter of the helix, threading the wire helix onto said screw thread by springing the helix open sufficiently to receive the rod, and then dipping the rod and coiled wire into molten solder.

6. A method for making a ground rod connection, comprising forming a helix in

a wire, forming a screw thread on a portion of a ground rod with the diameter of the root of the thread greater than the inner diameter of the helix, and threading the wire helix onto said screw thread by springing the helix open sufficiently to receive the rod, cross drilling the rod at one end of the thread, fastening one end of the wire in the hole by means of a channel pin, and then dipping the rod and coiled wire into molten solder.

7. In combination, a ground rod having a cross drilled hole therein, a helical groove in the rod terminating at one end adjacent the hole, a wire having one end held in the hole by a cylindrical grooved channel pin and an outwardly sprung helical coil portion received in the groove to elastically embrace the rod, and a layer of solder covering the wire coil and adjacent portion of the rod and connecting the wire to the rod.

In testimony whereof I affix my signature.

FRANK H. BANNER.
